poration of Delaware

Application May 26, 1937, Serial No. 144,789

44 Claims. (CL 200—135)

My invention relates, generally, to fuse devices and it has particular relation to the construction of fuse links that are intended to be replaced once they have blown. It is further particularly related to the construction of fuse links that are especially adapted for use in the secondary or low voltage, high current, circuit of a distribution transformer, although their use is not limited to this application.

The thermal duty to which a fuse device in the secondary or low voltage, high current, circuit of a distribution transformer is subjected is considerably greater than the thermal duty imposed on a fuse device in the primary or high voltage, low current, circuit of the transformer. This difference in thermal duty is caused by the requirement that the fuse device in the secondary circuit protect the transformer during overload and clear the circuit during overload or short circuit without blowing the primary fuse. Thus it must operate close to its minimum fusing current without deterioration.

The object of my invention, generally stated, is to provide a fuse link that will operate under the foregoing conditions and which may be readily and economically manufactured and installed.

An object of my invention is to provide for constructing a fuse link in such manner that it will operate close to its minimum fusing current at a relatively low temperature with little heat dissipation or watt loss and, at the same time, will not deteriorate because of flowing of metal, oxidation and the like.

A further object of my invention is to increase the resistance of a fuse element on flow of predetermined current therethrough by the interaction of two or more metals forming the element in such manner that the rupturing of the element is accelerated.

Another object of my invention is to take advantage of the alloying characteristics of two metals such as silver and tin, to effect the interruption of a circuit on flow of predetermined current therethrough.

Still another object of my invention is to provide a composite fusible element having a sheath formed of a metal having a relatively high conductivity enclosing a core formed of a metal having a lower conductivity.

A specific object of my invention is to provide a composite fusible element having a tin core and a silver sheath.

Another object of my invention is to provide for electrical connection to a composite fusible element comprising a core formed of metal hav-

ing a relatively low melting point and a surrounding sheath formed of a metal having a relatively high melting point in such manner that heat generated in the core is rapidly conducted away from it.

Still another object of my invention is to provide for interconnecting a metal sheathed fusible element and a stranded conductor in which the cross-sectional area of the latter is not limited by the size of the sheath.

A further object of my invention is to provide for indicating that a low voltage, high current, fuse device has operated.

A still further object of my invention is to provide for readily replacing a high current, low voltage, fuse link in a fuse housing.

Still another object of my invention is to provide for relieving a composite fusible element electrically interconnecting a pair of terminals biased apart by a spring, of the stress imposed by the spring.

Another object of my invention is to provide a readily replaceable fuse link construction employing a pair of terminals adapted to be biased apart and interconnected by a strain element and a composite fusible element formed by a low melting point core and a high melting point sheath.

Other objects of my invention will, in part, be obvious and in part appear hereinafter.

Accordingly, my invention is disclosed in the embodiments hereof shown in the accompanying drawings, and it comprises the features of construction, combination of elements and arrangement of parts which will be exemplified in the constructions hereinafter set forth, and the scope of the application of which will be indicated in the appended claims.

For a more complete understanding of the nature and scope of my invention reference may be had to the following detailed description taken in conjunction with the accompanying drawings, in which:

Figure 1 is a view, in side elevation, of one embodiment of my novel fuse link, certain parts being shown in section to more clearly illustrate the construction;

Figure 2 is a view, in front elevation, of a fuse link similar to that shown in Figure 1 and having a different length of core.

Figure 3 is a sectional view, at an enlarged scale, taken along the line 3—3 of Figure 2;

Figure 4 is a view, in front elevation, of another embodiment of a fuse link constructed in

accordance with my invention, a portion being shown in section;

Figure 5 is a sectional view taken along the line 5—5 of Figure 4;

Figure 6 is a view, partly in front elevation and partly in section, illustrating another embodiment of my invention;

Figure 7 is a sectional view taken along the line 7—7 of Figure 6;

Figure 8 is a view, in side elevation, of a fuse housing in which the fuse links shown in the preceding figures may be positioned;

Figure 9 is a longitudinal sectional view taken along the line 9—9 of Figure 8;

Figure 10 is a detail cross-sectional view taken along the line 10—10 of Figure 9;

Figure 11 is a detail sectional view taken along the line 11—11 of Figure 9;

Figure 12 is a fragmentary sectional view of a fuse device of the liquid arc extinguishing type in which another embodiment of the present invention is employed;

Figure 13 is a sectional view, at an enlarged scale, taken along the line 13—13 of Figure 12;

Figure 14 is a view, at an enlarged scale, of the composite fusible element shown in Figure 12, the sheath being shown in section and the remaining parts being shown in elevation;

Figure 15 is a longitudinal sectional view of a replaceable fuse link employing a strain element and a composite fusible element;

Figure 16 is a sectional view, at an enlarged scale, taken along the line 16—16 of Figure 15; and

Figure 17 is a sectional view, at an enlarged scale, taken along the line 17—17 of Figure 15.

Referring now particularly to Figure 1 of the drawings, it will be observed that the reference character 15 designates, generally, a fuse link which includes a composite fusible element shown generally at 16, to which flexible conductors 17, in the form of a plurality of strands of wire, are connected. It will be understood that the flexible conductors 17 may be connected to suitable circuit terminals in the circuit in which the fuse link 15 is connected for projecting the same. The composite fusible element 16 comprises a core 18 and a sheath or sleeve 19. The core 18 is composed of a metal having a relatively low melting point, such as tin, while the sheath or sleeve 19 is composed principally of a metal having a relatively high melting point, such as silver.

The action on blowing of the composite fusible element 16, formed of two distinct metals such as silver and tin which are capable of alloying with each other, is entirely different from that which takes place when a fusible element is formed entirely of metal, such as silver, tin, lead, zinc or aluminum or alloys of these or other metals. When sufficient current flows through a fusible element of the latter type to heat it to its melting point, the metal passes from the solid to the liquid state and, while the heat of fusion is being applied, the temperature remains substantially constant. Since the metal is in the liquid state and unrestrained, it flows away from its solid state position or is vaporized by the heat of the resulting arc and opens the circuit. This action takes place at a rate depending solely upon the heat generated in the fusible element for a given set of operating conditions.

When sufficient current flows through a composite fusible element under this same set of operating conditions to raise its temperature to the melting point of the lower of the two metals

forming it, an alloying action begins to take place. Since the melting point of the alloy thus formed is lower than that of either of the two metals, the change from the solid to the liquid state is accelerated. Moreover, since the resistance of the alloy formed is greater than the combined resistance of the two metals in the solid state, the change is further accelerated for the reason that the heat generated in the fusible element is a function of its resistance. Once the alloying action sets in, the change of a portion at least of the fusible element from the solid to the liquid state takes place with extreme rapidity due to changes in these two factors, namely, melting point and resistance. At the same time, until the melting point of the lower of the two metals is reached, substantially no change takes place. With a proper proportioning of the relative amounts of the two metals forming the composite fusible element 16, it is possible to provide a fusible element the characteristics of which will remain unchanged until it is heated to the temperature at which the lower melting point metal melts. At this definite point the change from the solid to the liquid state begins to take place and, because of the lowering of the melting point of the resulting alloy and the increase in its resistance, the action is somewhat cumulative and positive circuit interruption takes place. It is then possible to more accurately predict the conditions under which a composite fusible element, such as a silver sheathed tin element, will blow than is the case when the element is formed of a metal such as pure tin for example.

In the design of fusible elements it is necessary not only to consider the current at which an element will blow when it is heated to fusion temperature for the first time but also it is necessary to consider the operating characteristics of the element after it has once been heated nearly to the melting point, such as may occur as a result of transients, short time overloads and the like, and then the temperature of the element decreases so that, at that time, it does not blow. Under such conditions there may be a change in the crystal structure of the metal as well as a change in its physical appearance.

Considering, for example, a fusible element formed of pure tin, it has been found that it will conduct a certain overload for a given time without blowing but the application of the same overload conditions for the same time subsequently may cause it to blow. This somewhat inconsistent action may be attributed to the fact that the tin fusible element is necked down or somewhat reduced in cross section intermediate its ends because of its having been heated to a temperature approaching its melting point so that the same cross-sectional area is not available for conducting current as was previously the case. With such a fusible element it is not possible to accurately predict just when it will blow under substantially all operating conditions. When the composite fusible element 16 is employed, this necking down action cannot take place for the reason that the tin core 18 is restrained by the surrounding sheath or sleeve 19 of silver. However, as soon as the fusible element 16 is heated to a temperature that is sufficient to initiate the melting of the tin core 18, the alloying action takes place with the accompanying increase in resistance and the circuit is positively opened without delay.

The action of a fusible element of the prior art, such as an element composed of silver, tin,

lead, etc., as compared to the action of a composite fusible element, formed of two metals such as silver and tin capable of alloying with each other and so arranged that such alloying takes place, may be likened to the rolling of two balls up two inclined planes. In the case of the fusible element of the prior art the inclined plane has a level surface at the top onto which the ball is rolled on reaching this position. For certain metals, such as tin, the slope of this incline changes each time that the ball is rolled close to the top but not onto the level surface. In the other case with the composite fusible element the slope of the incline does not change under these conditions and the ball at the top of the inclined plane does not roll onto a flat surface but rather rolls onto a surface that is curved downwardly with a curvature that increases as the ball passes the uppermost position. This ball then drops at an accelerated rate, corresponding to the rapid change from the solid to the liquid state of the composite fusible element, while the other ball rolls along a flat surface corresponding to the relatively slow change from the solid to the liquid state of the fusible elements of the prior art.

Other important operating characteristics are obtained by the provision of the composite fusible element 18 formed by the low melting point core 18 and the high melting point sheath or sleeve 19. The durability characteristics of silver are obtained as well as the low operating temperature of tin for the reason that the temperature of the element 18 never exceeds the melting temperature of the core 18 by any great amount. Due to this relatively low temperature characteristic, the fuse housing in which the fuse link 18 is positioned is not damaged when it is operated for relatively long periods close to the minimum fusing current, as it may be if the fusible element were composed entirely of silver, or other high melting point metal. It will be understood that a fusible element composed entirely of silver will operate at a relatively high temperature when it is called upon to carry current for appreciable lengths of time close to the minimum fusing current. By combining the characteristics of tin and silver it is possible to take advantage of the low temperature at which the composite fusible element 18 will operate over sustained periods of current flow close to the minimum fusing current and, at the same time, to obtain the durability characteristic of silver because of its non-deteriorating ability.

As shown in Figure 1 of the drawings, the ends 20 of the sleeve or sheath 19 extend well beyond the ends 21 of the core 18. The ends 22 of the flexible conductors 17 extend into the ends 20 of the sleeve or sheath 19 and into abutting relation with the ends 21 of the core 18. The ends 20 of the sleeve or sheath 19 are then deformed, as illustrated, onto the ends 21 and 22 of the core 18 and conductor 17, respectively, to securely hold the same therein. Since the ends 22 of the flexible conductors 17 are readily deformable, they are well suited for the purpose of filling the ends 20 of the sleeve or sheath 19 to provide electrical connection thereto and to conduct heat away from the core 18.

With a view to improving the connection between the composite fusible element 18 and the flexible conductors 17, tubular connectors 23 in the form of copper sleeves may be positioned around the ends 20 of the sleeve or sheath 19 and deformed therewith, as shown. The tubular

connecting sleeves 23 serve to reinforce the ends 20 of the sleeve or sheath 19, particularly at elevated temperatures, and to hold the same in tight fitting engagement with the ends 22 of the flexible conductors 17.

It will be understood that the several parts forming the fuse link 18 may be of different relative size than illustrated in the drawings. For the construction of a fuse link for one particular rating the following dimensions and materials were employed. The core 18 may be composed of pure tin wire $1\frac{1}{4}$ " long and having a diameter of .107". The sleeve or sheath 19 may be composed of pure silver tubing having a length of $2\frac{1}{4}$ " and an inside diameter of .128" and an outside diameter of .148". The copper sleeves 23 are $\frac{3}{8}$ " long, while the flexible conductors 17 may be of any suitable length, for example, 3" long. Tests have indicated that the temperature of the sheath 19 of a fuse link having these dimensions will be about 250° C. just prior to blowing. It is pointed out that these figures are by way of illustration only and are not to be construed as in any way limiting the proportions in which the various elements may be employed.

Because of the presence of the low melting point core 18 the fuse link 18 will operate at a relatively low temperature even though it is called upon to conduct current in an amount that is close to the minimum fusing current. It is then possible to provide a suitable housing for the fuse link 18 in close proximity thereto which will not be subjected to a relatively high temperature, such as the temperature that obtains when a fuse link formed solely of silver is operated close to its minimum fusing current.

In Figure 2 of the drawings another embodiment of the invention is illustrated. The fuse link 18' there shown is similar to the fuse link 18 shown in Figure 1. However, the core 18' is relatively somewhat shorter and the ends 22' of the flexible conductors 17 extend well within the sleeve or sheath 19 and beyond the deformed ends thereof. This construction is desirable for two reasons. First, it is unnecessary to deform the solid tin forming the core, as is the case in the construction shown in Figure 1. Second, the heat that is generated in the tin core 18' is more readily conducted away since the flexible conductors 17 are formed of strands of copper and are, therefore, capable of conducting heat much more readily than is tin.

It will be understood that the length of the low melting point core relative to the length of the high melting point sheath may be varied as well as the relative cross-sectional areas, as may be desired. It will also be understood that other metals than silver and tin may be employed. For example, copper may be employed for the sheath or sleeve and the core may be formed of bismuth. Also the core may be formed of zinc or lead or other like metals. It is not intended to limit this invention to the use of pure metals for the core and sheath. Either or both of these members may be formed of suitable alloys as may be found to be desirable. While the present invention is concerned primarily with the binary alloying action that takes place when the fusible element is heated to a temperature approximating the melting point of the core, alloys composed of three or more metals may be formed if the sheath or core or both are formed of alloy metal rather than pure metal.

It will now be apparent that I have provided a new method of opening an electric circuit on

flow of current therein above a predetermined current flow by the action of a composite fusible element connected in series with the circuit and formed by two distinct metals, one being encased in the other and having a lower melting point than the other and being capable of alloying with the other, which comprises:

- (1) Heating the composite fusible element to a temperature sufficient to melt the lower melting point metal and insufficient to melt the higher melting point metal;
- (2) Forming an alloy having a melting point lower than that of the lower melting point metal, thereby accelerating the change of a portion of the fusible element from the solid to the liquid state; and
- (3) At the same time increasing the resistance of the fusible element, due to the formation of the alloy, to further accelerate the change in state by the generation of additional heat.

By varying the relative cross-sectional areas of the core and sheath or sleeve, by varying the relative lengths thereof, and by varying the heat conducting capacity between the core and the terminals, it is possible to provide a wide variety of fusible elements the operating characteristics of which can be accurately predetermined. Such fusible elements may be applied in circuits where highly selective action is required between two or more fuse devices connected in series circuit relation, depending upon the particular point at which the fault occurs or at which the overload occurs that requires the circuit to be interrupted.

In Figures 4 and 5 of the drawings another embodiment of the invention is illustrated. The fuse link, shown generally at 26, includes a composite fusible element, shown generally at 27, that includes a core 28, formed of a low melting point metal, such as tin, and a sleeve or sheath 29, formed of a metal having a relatively high melting point, such as silver. These metals are chosen for the reasons set forth hereinbefore. Circuit connections are provided by the flexible conductors 30.

In the construction of the fuse link 15, shown in Figures 1 and 2 of the drawings, the size of the flexible conductors 17 is limited by the size of inside diameter of the end portions 20 of the sleeve or sheath 19. For the purpose of providing for the use of flexible conductors the size of which is not dependent upon the inside diameter of the high melting point sleeve or sheath, the terminal connectors 31 are provided between the ends of the composite fusible element 27 and the flexible conductors 30. The terminal connectors 31 are somewhat tubular in construction and they may be formed from suitable lengths of solid copper rod. The ends 32 are provided with suitably drilled apertures for receiving the ends of the flexible conductors 30. These ends 32 are flattened onto the ends of the flexible conductors 30 in order to secure them in position and provide electrical contact engagement therewith. In like manner the other ends 33 of the terminal connectors 31 are provided with suitably drilled apertures for receiving the composite fusible element 27 formed by the core 28 and the sleeve or sheath 29. Initially the core 28 and sheath 29 are of substantially the same length and the inside diameters of the ends 33 are such as to readily permit the insertion of the ends of the composite fusible element 27. The ends 33 are

then flattened, as shown, to provide the desired connection.

It will be observed that the intermediate portions 34 between the ends 32 and 33 of the terminal connectors 31 form closures for the drilled apertures in the ends 33. These closures prevent the escape of the core metal 28. If desired, the core 28 may be substantially shorter than the sleeve or sheath 29, as shown in Figure 2 for example, and the ends of the sleeve or sheath may be filled with conducting material, such as strands of copper wire as will hereinafter appear, to conduct heat away from the core 28 for the purpose of increasing the rating of the link as well as for other purposes which will also be set forth.

With a view to protecting the composite fusible element from injury while it is being handled and carried about, the construction shown in Figures 6 and 7 of the drawings may be employed. As there shown, a fuse link 37 is provided having terminal connectors 38 that are arranged to interconnect a composite fusible element, shown generally at 39 and comprising a low melting point core 40 and a high melting point sleeve or sheath 41 formed of tin and silver, respectively, for the reasons set forth hereinbefore, and flexible conductors 42. Intermediate the ends of the terminal connectors 38 knurled portions 43 are provided for receiving and holding the ends of a sleeve 44 formed of a suitable insulating material such as fiber. It will be noted that the sleeve 44 completely encloses the composite fusible element 39 and therefore serves to protect it from injury during handling thereof. In addition, the sleeve 44, when composed of a material such as fiber, serves to evolve arc extinguishing gases, on the occurrence of an arc, that assist in extinguishing the same.

In order to house the fuse link 37, shown in Figure 6 of the drawings, or the fuse links shown in Figures 1 and 4 of the drawings, the housing shown generally at 46 in Figures 8 and 9 may be employed. The housing 46 comprises a fuse tube 47 that is preferably formed of fiber and has relatively thick walls, with a longitudinal bore 48 for receiving the fuse link, such as the fuse link 37. The ends of the fuse tube 47 are externally threaded for receiving in threaded engagement therewith fuse tube ferrules 49. The outer ends 50 of the ferrules 49 are generally cylindrical in shape and are provided with cylindrical apertures 51 therethrough that are arranged to form extensions of the bore 48. Each of the cylindrical end portions 50 is provided with a longitudinal slot 52 through which the flexible conductors 42 may be positioned for placing them around the cylindrical portions 50, as is more clearly shown in Figure 10 of the drawings. It will be observed that a shoulder portion 53 is provided intermediate the ends of the fuse tube ferrules 49 for receiving the flexible conductors 42 in contact engagement therewith. Suitable pins 54 extend through the threaded ends of the fuse tube 47 and the ferrules 49, as shown, for holding them securely in place.

With a view to holding the flexible conductors 42 in position, cable clamp nuts 55 are provided. It will be noted that the inner ends of the clamp nuts 55 are internally threaded for engaging corresponding external threads about the inner ends of the ferrules 49. Shoulder portions 56 are provided, having faces parallel to the faces of the shoulders 53. When the clamp nuts 55 are

screwed into position with the flexible conductors 42 disposed as shown around the cylindrical ends 58 of the ferrules 48, they will be clamped between the shoulder portions 53 and 56.

It is desirable that some indication be provided that the fuse link 37 has blown. In most cases, when the fuse link 37 blows, a considerable volume of gas is generated inside of the bore 48 of the fuse tube 47. Advantage is taken of the generation of gas pressure inside of the fuse tube 47 by providing readily expellable plugs 57 in cylindrically shaped extensions 58 of the clamp nuts 55. The plugs 57 are preferably formed of cork and they may be painted a suitable color, for example, red, as shown, to more readily provide for determining whether or not the fuse device has operated.

It will be understood that the fuse housing 46 may be placed in a suitable support device and that suitable terminals may be provided for connection to the cylindrical end portions 58 of the clamp nuts 55.

As indicated, considerable pressure may be generated within the bore 48 of the fuse tube 47 when the fuse device 37 blows. If the housing 46 were arranged to be vented from one end only, it would be necessary to provide a support that would have sufficient strength to withstand the reaction applied to the housing. In order to avoid this difficulty the housing 46 is vented at both ends, with the result that pressure generated within the bore 48 may be relieved in opposite directions, so that substantially no longitudinal reaction will be applied to the fuse tube 47. Ordinarily, both of the plugs 57 will be expelled and their absence will indicate that the fuse device has operated. Under certain conditions only one of the plugs 57 may be expelled, and, in a few cases, when the fuse link 37 blows as a result of a slight sustained overload, it may be possible that sufficient pressure will not be generated within the bore 48 to cause the plugs 57 to be expelled. However, this condition is not often encountered.

Since the fuse tube 47 is formed of a material such as fiber, gases which assist in extinguishing the arc formed on blowing of the fuse link 37 are evolved from the bore 48. The blast action thereby created materially assists in quickly extinguishing the arc.

The present invention may be embodied in a fuse device of the blast action, arc extinguishing type, such as shown in the co-pending application of Nicholas J. Conrad, Serial No. 470,416, filed July 24, 1930, and assigned to the assignee of this application, now Patent No. 2,091,430. This embodiment of the invention is illustrated in Figure 12 of the drawings.

As shown, a fuse device, designated generally by the reference character 61, is provided, that is generally of the type disclosed in the copending application of Conrad, but which is provided with a fuse link, shown generally at 62, that is constructed in accordance with this invention. The details of construction of the fuse device 61 will be set forth herein only insofar as is necessary to illustrate the present invention.

The fuse device 61 includes a sleeve or housing 63 that may be formed of glass or "Bakelite" and it has as its ends suitable terminal ferrules, one of which is shown at 64. A vent cap 65 is suitably pressed onto the upper end of the ferrule 64 and is adapted to be blown off on generation of sufficient pressure inside of the sleeve or housing 63, when the fuse link 62 blows. A mounting

plate 66, formed of insulating material, is threaded into the ferrule 64 for mounting therein an arcing tube 67 that also is formed of a suitable insulating material such as "Bakelite." As shown, the mounting plate 66 and the arcing tube 67 are provided with cooperating flanges by means of which the latter is supported by the former. Suitable washers 68, formed of readily frangible material, such as "Bakelite," are secured to the mounting plate 66 by screws 69 in overlapping relation with the arcing tube 67 to hold the same in position until sufficient pressure is generated within the housing or sleeve 63 to blow it out of its upper end.

The fuse link 62 is provided with upper and lower terminals 70 and 71. The upper terminal 70 is mounted in a support spider 72 and is secured thereto by a nut 73. The lower terminal 71 is provided with outwardly extending pins 74 that are arranged to carry a liquid director 75 that is retracted with the terminal 71 on blowing of the fuse link 62 by a coil tension spring 76 to direct liquid, which fills the housing or sleeve 63 to the level indicated, into the arcing chamber or tube 67 for assisting in extinguishing the arc drawn therein. A flexible conductor 77 is provided for interconnecting the lower terminal 71 and the lower ferrule of the housing or sleeve 63, as will be readily understood.

The upper and lower terminals 70 and 71 are arranged to be electrically interconnected by a composite fusible element that is shown generally at 80. The fusible element 80 extends into suitable drilled apertures 82 and 83 in the opposing faces of the terminals 70 and 71. In order to relieve the fusible element 80 of the tension stress that would otherwise be imposed by the spring 76, a tension element 84 in the form of a wire composed of a high strength metal, such as a nickel-chromium alloy, is also provided between the terminals 70 and 71 with its corrugated ends 85 disposed in suitable apertures 86 and 87 therein.

With a view to protecting the fusible element 80 and the strain element 84 of the fuse link 62 during installation, and from vibration after installation, a sleeve 88 formed of suitable insulating material such as "Bakelite" is provided around them and around suitable cylindrically shaped portions of the terminals 70 and 71, as illustrated. The sleeve 88 is provided with apertures 89 adjacent its ends to provide for the escape of liquid therefrom so that no liquid will remain in engagement with the fusible element 80 when the fuse device 61 is in the upright position for the purpose of avoiding change in its time-current characteristics.

The details of construction of the fusible element 80 are shown more clearly in Figure 14 of the drawings. As there shown, the fusible element 80 comprises a core 91, formed of a suitable low melting point metal such as tin, and a sleeve or sheath 92, formed of a relatively high melting point metal such as silver. The ends 93 of the sleeve or sheath 92 extend substantial distances beyond the ends of the core 91 and these ends are filled with short lengths 94 of conductive material formed by a plurality of small strands of wire. If desired, metal plugs may be substituted for the strands of wire 94. These plugs would be preferably formed of high heat conducting metal such as silver in order to readily conduct the heat generated in the core 91 to the terminals 70 and 71.

As indicated hereinbefore, the ends of the fu-

sible element 80 extend into suitable apertures 82 and 83 in the terminals 70 and 71. These ends are secured therein by deforming the adjacent wall of the terminals, as indicated at 95 in Figure 13 of the drawings. A suitable blunt ended tool is provided for deforming the adjacent terminal material to provide not only for securely holding the fusible element 80 in place, but also to provide for electrical contact engagement therewith.

In a similar manner the corrugated ends 85 of the strain element 84 are secured in the apertures 86 and 87 of the terminals 70 and 71. As indicated at 96 in Figure 13, the adjacent wall of the upper terminal 70 is deformed onto the corrugated end 85 in the aperture 86.

Since the ends of the composite fusible element 80 are secured to the terminals 70 and 71 by deforming a portion of the walls thereof, it is desirable that these ends be so constructed that the deforming operation may be readily and efficiently performed, and the desired contact engagement obtained. It is for this purpose that the ends 93 of the sleeve or sheath 92 are preferably filled with the readily deformable strands 94. Since the core metal 92 may become softened when the fuse link 62 is called upon to conduct current for sustained periods close to the minimum fusing current, it is further desirable that some material such as copper having a higher melting point be provided in the ends 93 of the sleeve or sheath 92 so that the contact engagement therewith will not be impaired under these operating conditions.

When the composite fusible element 80 is employed in a liquid fuse of type shown at 61 in Figure 12 of the drawings, an important improvement in operating characteristics is obtained as compared with the use therein of a fusible element, such as pure silver. This improvement resides in the lower wattage required to be dissipated in the form of heat when the composite fusible element is present for the reason that its operating temperature is much lower than that of a silver fusible element when conducting current close to its minimum fusing current. The major portion of the heat that is generated in the liquid fuse is conducted away from it through its end terminals, such as the ferrule 64. It will be noted that this ferrule is cemented onto the glass housing 63. It is essential for satisfactory operation of a liquid fuse that a fluid tight seal be maintained to insure that the insulating properties of the liquid will remain unchanged so that, on operation, it will be capable, not only of assisting in extinguishing the arc, but also of providing a suitable insulating medium of high dielectric strength between the terminals after the circuit has been interrupted. If excessive heat is required to be conducted away from the fusible element, there is a tendency for the cement to become softened with the result that the fluid tight seal provided thereby may be destroyed.

It is desirable to incorporate the composite fusible element in what is termed in the trade a "Universal fuse link." Such links generally comprise a pair of relatively infusible terminals that are interconnected by fusible means. A sleeve of insulation is ordinarily secured to one of the terminals and it extends over the fusible means and other terminal to protect the link during handling and to provide certain arc extinguishing characteristics. Such links are ar-

ranged and constructed so that they are interchangeably adapted to be inserted in practically any of the commercial types of fuse tube housings that are now being sold.

Such a construction is illustrated in Figure 15 of the drawings. As there shown, the reference character 100 designates, generally, a replaceable fuse link of the universal type that is provided with a pair of relatively infusible terminals 101 and 102 that are arranged to be interconnected by a composite fusible element 103 and a strain element 104. The fusible element 103 may be constructed similarly to the fusible element 80 as shown in detail in Figure 14 of the drawings.

The terminal 101 is provided with a threaded portion 105 on which is screwed a cap 106. For certain types of mounting the cap 106 is required, while for other types the cap 106 is removed and the link 100 is threaded into the corresponding socket in the fuse housing. The terminal 101 is knurled, as indicated at 107, intermediate its ends for receiving a sleeve 108, formed of a suitable insulating material such as paper, the upper end of the sleeve 108 being crimped onto the knurled portion 107 and secured in position by a retaining ring 109 that is crimped thereon.

As shown more clearly in Figure 16, the lower end portion 112 of the terminal 101 is provided with longitudinally drilled apertures 113 and 114 for receiving the ends of the fusible and strain elements 103 and 104. The outer surface of the lower portion 112 is deformed, as shown at 115 and 116 to secure the ends of the fusible and strain elements 103 and 104 therein.

The upper end portion 117 of the lower terminal 102 is formed similarly to the lower portion 112 of the terminal 101 for receiving the other ends of the fusible and strain elements 103 and 104. The outer surface of this portion is likewise deformed to securely hold these elements in position. Since the ends of the sheath forming a part of the composite fusible element 103 are filled with readily deformable material, such as the flexible conductors 94, (Figure 14), its ends may be readily deformed as described hereinbefore, so that proper contact engagement will be provided with the terminals 101 and 102 and the tin core will not be permitted to flow when it is in the softened state.

The lower end 118 of the terminal 102 is provided with an axially drilled aperture 119 for receiving one end of a flexible conductor 120 that comprises a plurality of strands of wire. As shown in Figure 17, the opposite sides of the lower end portion 118 are deformed inwardly both longitudinally and transversely for the purpose of securing the flexible conductor 120 therein and maintaining contact engagement therewith under relatively high pressure.

Since this particular terminal construction, is illustrated and described in the copending application, Serial No. 138,188, filed April 21, 1937, by myself and Sigurd I. Lindell, and assigned to the assignee of this application, a more detailed description will not be set forth herein.

With a view to providing for connection to an external terminal, a cone terminal 121 is pressed onto the flexible conductor 120. It will be understood that the fuse link 100 may be mounted in fuse housings in which one or more springs are provided for biasing the terminals 101 and 102 apart so that the arc may be rapidly extinguished. In such case, it will be understood that the strain

element 184 relieves the fusible element 183 of the stress that would otherwise be imposed thereon by the biasing forces. However, it will be understood that the fuse link 180 may be mounted in fuse housings in which springs or other biasing means are not employed.

Since certain further changes may be made in the foregoing constructions, and different embodiments of the invention may be made without departing from the scope thereof, it is intended that all matter set forth in the foregoing description and shown in the accompanying drawings shall be interpreted as illustrative and not in a limiting sense.

I claim as my invention:

1. In a fuse, in combination, a core formed of metal having a relatively low melting point, a metal sheath having a relatively high melting point and forming a self-supporting container for said core unbonded thereto with at least one end extending beyond the corresponding end of said core, and metal plug means extending into said one end of said metal sheath for conducting heat away from said core.

2. In a fuse, in combination, a core formed of metal having a relatively low melting point, a metal sheath having a relatively high melting point and forming a container for said core with at least one end extending beyond the corresponding end of said core, and a flexible conductor formed by a plurality of strands of wire extending into said one end of said metal sheath and said one end being deformed thereon.

3. In a fuse link, in combination, a core formed of metal having a relatively low melting point, a metal sheath having a relatively high melting point and forming a container for said core with at least one end extending beyond the corresponding end of said core, a flexible conductor formed by a plurality of strands of wire extending into said one end of said metal sheath in abutting relation to the adjacent end of said core, and a metal sleeve around said one end of said metal sheath, said metal sleeve and said one end of said metal sheath being deformed about said flexible conductor.

4. A fuse comprising, in combination, a core formed of metal having a relatively low melting point, a metal sheath having a relatively high melting point and forming a container for said core of such length that its ends extend beyond the ends of said core, and conductor means extending into said ends of said metal sheath for conducting heat away from said core.

5. A fuse comprising, in combination, a core formed of metal having a relatively low melting point, a metal sheath having a relatively high melting point and forming a container for said core of such length that its ends extend beyond the ends of said core, and a pair of flexible conductors each formed by a plurality of strands of wire extending into said ends of said metal sheath and said ends being deformed thereon.

6. A fuse link comprising, in combination, a core formed of metal having a relatively low melting point, a metal sheath having a relatively high melting point and forming a container for said core of such length that its ends extend beyond the ends of said core, a pair of flexible conductors each formed by a plurality of strands of wire extending into said ends of said metal sheath and into abutment with the ends of said core, and a metal sleeve around each end of said metal sheath, said ends of said metal sheath and said

sleeves thereon being deformed about said flexible conductors.

5 7. In a fuse link, in combination, a metal core, a self-supporting continuous container surrounding said core formed of metal which alloys therewith on flow of current sufficient to melt the same, a terminal conductor, and a terminal connector having one end adapted to receive said container and said core and to retain the latter in the liquid state and the other end adapted to receive said terminal conductor.

10 8. In a fuse link, in combination, a metal core, a self-supporting continuous container surrounding said core formed of metal which alloys therewith on flow of current sufficient to melt the same, a terminal conductor, a terminal connector having one end adapted to receive said core and container and the other end adapted to receive said terminal conductor, and closure means between said ends of said terminal connector adapted to retain said core in the liquid state.

15 9. In a fuse link, in combination, a metal core, a self-supporting container surrounding said core formed of metal which alloys therewith on flow of current sufficient to melt the same, a terminal conductor, and a terminal connector having one end adapted to receive said container and core and to retain the latter in the liquid state and the other end adapted to receive said terminal conductor, said one end of said terminal connector being deformed about said container and said other end of said terminal connector being deformed about said terminal conductor.

20 35 10. In a fuse link, in combination, a core composed principally of tin, a continuous tubular container composed principally of silver surrounding said core, a flexible conductor, and a terminal connector having one end adapted to receive said continuous container and said core and to retain the latter in the liquid state and the other end adapted to receive said flexible conductor.

40 45 11. In a fuse link, in combination, a core composed principally of tin, a tubular container composed principally of silver surrounding said core, a flexible conductor, and a terminal connector having one end adapted to receive said container and said core and to retain the latter in the liquid state and the other end adapted to receive said flexible conductor, said one end of said terminal connector being deformed about said core and container and said other end of said terminal connector being deformed about said flexible conductor.

50 55 12. A fuse link comprising, in combination, a metal core, a self supporting container surrounding said core formed of metal which alloys therewith on flow of current sufficient to melt the same, a pair of flexible conductors, and a pair of terminal connectors each having one end adapted to receive said container and said core and to retain the latter in the liquid state and the other end adapted to receive one of said flexible conductors.

60 65 70 75 13. A fuse link comprising, in combination, a core composed principally of tin, a tubular container composed principally of silver surrounding said core, a pair of flexible conductors formed by a plurality of strands of wire, and a pair of tubular terminal connectors each having one end adapted to receive said container and said core and to retain the latter in the liquid state and the other end adapted to receive one of said flexible conductors.

14. A fuse link comprising, in combination, a core composed principally of tin, a tubular container composed principally of silver surrounding said core, a pair of flexible conductors formed by a plurality of strands of wire, a pair of tubular terminal connectors each having one end adapted to receive said core and container and the other end adapted to receive one of said flexible conductors, and closure means intermediate the ends of each of said terminal connectors.

15. A fuse link comprising, in combination, a metal core, a self-supporting container surrounding said core formed of metal which alloys therewith on flow of current sufficient to melt the same, a pair of flexible conductors, a pair of terminal connectors each having one end adapted to receive said container and said core and to retain the latter in the liquid state and the other end adapted to receive one of said flexible conductors, and means mechanically interconnecting said terminal connectors in addition to said core and container.

16. A fuse link comprising, in combination, a metal core, a container surrounding said core formed of metal which alloys therewith on flow of current sufficient to melt the same, a pair of flexible conductors, a pair of terminal connectors each having one end adapted to receive said container and said core and to retain the latter in the liquid state and the other end adapted to receive one of said flexible conductors, and a sleeve surrounding said container and said terminal connectors.

17. A fuse link comprising, in combination, a metal core, a container surrounding said core formed of metal which alloys therewith on flow of current sufficient to melt said core, a pair of flexible conductors, a pair of terminal connectors each having one end adapted to receive said core and container and the other end adapted to receive one of said flexible conductors, a knurled portion intermediate the ends of each of said terminal connectors, and a sleeve formed of insulating material surrounding said container and interfitting with said terminal connectors at the knurled portions thereof.

18. In a fuse, in combination, a metal core, a container closely surrounding and extending beyond the ends of said core and formed of metal which alloys therewith on flow of current sufficient to melt the same, and means filling the ends of said container for holding said core in place in the molten state.

19. In a fuse, in combination, a metal core, a container closely surrounding and extending beyond the ends of said core and formed of metal which alloys therewith on flow of current sufficient to melt the same, readily deformable means filling the ends of said container for holding said core in place in the molten state, and a relatively infusible terminal interfitting with and deformed onto each of said ends of said container.

20. A fuse link comprising, in combination, a core formed principally of tin, a cylindrical sleeve formed principally of silver closely fitting around said core and extending a substantial distance beyond the ends of the same, and a plurality of strands of wire filling the extended ends of said sleeve for holding said core in place in the molten state.

21. A fuse link comprising, in combination, a core formed principally of tin, a cylindrical sleeve formed principally of silver closely fitting around said core and extending a substantial distance beyond the ends of the same, a plurality of

strands of wire filling the extended ends of said sleeve for holding said core in place in the molten state, and a relatively infusible terminal interfitting with and deformed onto each of said ends of said sleeve.

22. A fuse link comprising, in combination, a pair of relatively infusible terminals adapted to be biased apart by a spring; a composite fusible element electrically interconnecting said terminals including a metal core having a relatively low melting point, a metal sleeve surrounding said core and extending beyond its ends into said terminals, and a plurality of strands of wire filling the ends of said sleeve extending into said terminals; and a strain element extending into said terminals for relieving said fusible element of stress imposed by the spring tending to separate said terminals, said terminals being deformed onto the ends of said fusible and strain elements.

23. A fuse link comprising, in combination, a pair of relatively infusible terminals; a composite fusible element electrically interconnecting said terminals including a metal core having a relatively low melting point, a metal sleeve surrounding said core and extending beyond its ends into said terminals, and a plurality of strands of wire filling the ends of said sleeve extending into said terminals; a strain element extending into said terminals for relieving said fusible element of stress tending to separate said terminals, said terminals being deformed onto the ends of said fusible and strain elements, and a sleeve of insulation interfitting with said terminals and surrounding said fusible and strain elements.

24. A fuse link comprising, in combination, a pair of relatively infusible terminals, a composite fusible element electrically interconnecting said terminals including a core composed principally of tin, a sleeve composed principally of silver surrounding said core and extending beyond its ends into said terminals, and a plurality of strands of wire filling the ends of said sleeve extending into said terminals; and a strain element extending into said terminals for relieving said fusible element of stress tending to separate said terminals, said terminals being deformed onto the ends of said fusible and strain elements.

25. A fuse link comprising, in combination, a metal core, a self-supporting container surrounding said core composed of metal which remains substantially unchanged on flow of current sufficient to melt said core; a pair of relatively infusible terminals secured to the ends of said container and adapted to retain said core in the liquid state, one having a terminal fitting receiving portion and the other having a conductor receiving portion; and a flexible conductor secured in said conductor receiving portion.

26. A fuse link comprising, in combination, a metal core, a container surrounding said core formed of metal which alloys therewith on flow of current sufficient to melt the same; a pair of relatively infusible terminals secured to the ends of said container, one having a terminal fitting receiving portion and the other having a conductor receiving portion; a flexible conductor secured in said conductor receiving portion, and an insulating sleeve secured to said one of said terminals and extending over the other of said terminals.

27. A fuse link comprising, in combination; a pair of relatively infusible terminals, one having a terminal fitting receiving portion and the other having a conductor receiving portion; a fusible element electrically interconnecting said ter-

minals including a core formed of metal having a relatively low melting point and a surrounding self-supporting sheath formed of metal adapted to allow with said core on flow of current sufficient to melt the same, said terminals being adapted to retain said core in the liquid state, a strain element mechanically interconnecting said terminals, and a flexible conductor secured in said conductor receiving portion.

28. A fuse link comprising, in combination; a pair of relatively infusible terminals, one having a terminal fitting receiving portion and the other having a conductor receiving portion; a fusible element electrically interconnecting said terminals including a core formed of metal having a relatively low melting point and a surrounding sheath formed of metal adapted to alloy with said core on flow of current sufficient to melt the same, a strain element mechanically interconnecting said terminals, a flexible conductor secured in said conductor receiving portion, said terminals being deformed onto the respective ends of said fusible and strain elements and said flexible conductor, and an insulating sleeve secured to said one of said terminals and extending over the other of said terminals and around said fusible and strain elements.

29. In a fuse link, in combination, a core formed of metal having a relatively low melting point, a metal sheath having a relatively high melting point and forming a container for said core with at least one end extending beyond the corresponding end of said core, and a flexible conductor formed by a plurality of strands of wire secured in said one end of said metal sheath.

30. In a fuse, in combination, a tin core, a silver sheath forming a self-supporting container for said tin core and extending beyond the ends of the same, and metal means carried by said silver sheath at the ends of said tin core for conducting heat away therefrom.

31. In a fuse, in combination, a tin core, a silver sheath forming a self-supporting container for said tin core and extending beyond the ends of the same, and a metal plug within said silver sheath at each end of said tin core for conducting heat away therefrom.

32. In a fuse, in combination, a core formed of metal having a relatively low melting point, a metal sheath having a relatively high melting point and forming a container for said core and extending beyond the ends of the same, and metal means having relatively high thermal capacity and heat conductivity carried by said sheath at the ends of said core for conducting heat away therefrom and limiting the transmission of heat thereto.

33. In a fuse, in combination, a core formed of metal having a relatively low melting point, a metal sheath having a relatively high melting point and forming a container for said core and extending beyond the ends of the same, and a metal plug having relatively high thermal capacity and heat conductivity within said sheath at each end of said core for conducting heat away therefrom and limiting the transmission of heat thereto.

34. A fuse link comprising, in combination; a pair of relatively infusible terminals, one having a terminal fitting receiving portion and the other having a conductor receiving portion; a fusible element electrically interconnecting said terminals including a core formed of metal having a relatively low melting point and a surrounding sheath formed of metal adapted to alloy with said core on flow

of current sufficient to melt the same, a strain element mechanically interconnecting said terminals, a flexible conductor secured in said conductor receiving portion, and an insulating sleeve extending between said terminals and around said fusible and strain elements.

35. A fuse link comprising, in combination; a pair of relatively infusible terminals, one having a terminal fitting receiving portion and the other having a conductor receiving portion; a fusible element electrically interconnecting said terminals including a tin core and a surrounding silver sheath, a strain element mechanically interconnecting said terminals, a flexible conductor secured in said conductor receiving portion, and an insulating sleeve extending between said terminals and around said fusible and strain elements.

36. In a fuse, in combination, a core formed of metal having a relatively low melting point, a metal sheath having a relatively high melting point and forming a container for said core and extending beyond the ends of the same, metal plug means filling the ends of said sheath for conducting heat away from said core, and a relatively infusible terminal interfitting with and deformed onto each end of said sheath and the metal plug means therewithin.

37. In a fuse, in combination, a core formed of metal having a relatively low melting point, a metal sheath having a relatively high melting point and forming a container for said core, and terminal means at the ends of said sheath at least one of which includes flexible conductor means and metallic sleeve means cooperating with said sheath and flexible conductor means whereby the same are mechanically and electrically interconnected.

38. In a fuse, in combination, a tin core, a silver sheath for said core, and terminal means at the ends of said sheath at least one of which includes flexible conductor means and metallic sleeve means cooperating with said sheath and flexible conductor means whereby the same are mechanically and electrically interconnected.

39. In a fuse device, a composite current carrying element comprising a tin core and an impervious silver sheath therefor having a substantial thickness whereby it carries the major portion of the normal load current flowing through the element and is capable of alloying with the tin core when heated to its melting temperature, thereby increasing the resistance of the element so that it ruptures once the alloying action is initiated.

40. In a fuse, in combination, a core formed of metal having a relatively low melting point, a sheath formed of metal having a relatively high melting point surrounding said core and extending beyond the ends of the same, and an imperforate plug formed of metal having a relatively high melting point filling each end of said sheath and engaging the ends of said core for conducting heat away therefrom.

41. In a fuse, in combination, a core formed of metal having a relatively low melting point, a sheath formed of metal having a relatively high melting point surrounding said core and extending beyond the ends of the same, an imperforate plug formed of metal having a relatively high melting point filling each end of said sheath and engaging the ends of said core for conducting heat away therefrom, and a relatively infusible terminal interfitting with and deformed onto each end of said sheath.

42. In a fuse, in combination, a tin core, a silver sheath surrounding said core and extending beyond the ends of the same, and an imperforate plug formed of metal having a relatively high melting point filling each end of said sheath and engaging the ends of said core for conducting heat away therefrom.

43. In a fuse, in combination, a tin core, a silver sheath surrounding said core and extending beyond the ends of the same, and a silver plug filling each end of said sheath and engaging the ends of said core for conducting heat away therefrom.

44. In a fuse, in combination, a tin core, a silver sheath surrounding said core and extending beyond the ends of the same, an imperforate plug formed of metal having a relatively high melting point filling each end of said sheath and engaging the ends of said core for conducting heat away therefrom, and a relatively infusible terminal interfitting with and deformed onto each end of said sheath.

HUGH A. TRIPPLETT.
